PLATFORM SCAFFOLD

Homer B. Waltz, Canton, Ohio

Application April 13, 1945, Serial No. 588,127

6 Claims. (Cl. 304—29)

The invention relates to scaffolds and more particularly to a folding platform scaffold adapted for use by workmen for work on ceilings, walls and the like.

The object of the invention is to provide a scaffold of this type which may be easily and readily extended for use and folded or collapsed for transporting or storage.

Another object is to provide a scaffold of this type in which the platform may be quickly and easily adjusted to various heights.

A further object is to provide a platform scaffold having a ladder associated therewith so that the workman may easily and safely climb up to the platform.

A still further object is to provide a ladder scaffold in which the platform of the scaffold forms the top step of the ladder.

Still another object of the invention is to provide a scaffold of this type made up of one or more units each of which comprises two upright supporting frames adjustably connected together by lazy tong levers, and means for supporting a platform between the upright supporting frames at any desired or necessary height.

Still another object is to provide a scaffold of this type in which the platform is supported upon vertically adjustable cross bars adjustably mounted upon the upright frames and having means for clamping them rigidly in any adjusted position.

A still further object is to provide a scaffold of this character in which one end of each platform section is rigidly connected to one of the vertically adjustable cross bars and the other end thereof is adapted to rest upon the adjustable cross bar of an adjacent upright supporting frame with positive means for locking the platform against movement relative to the last named cross bar.

The above objects together with others which will be apparent from the drawing and following description, or which may be later referred to, may be attained by constructing the improved scaffold in the manner illustrated in the accompanying drawing, in which:

Figure 1 is a perspective view of a platform scaffold embodying the invention showing the same in extended position;

Fig. 2 is a perspective view of the improved scaffold in the folded or collapsed position;

Fig. 3 an enlarged detail sectional view showing the manner in which each section of the platform is hingedly connected to the adjustable cross bar of one upright supporting frame and rests

upon and is secured to the adjustable cross bar or an adjacent supporting frame;

Fig. 4 a longitudinal plan sectional view through the upper portion of one of the upright supporting frames showing the adjustable cross bar thereon, with parts broken away for the purpose of illustration; and

Fig. 5 a transverse sectional view taken as on the line 5—5, Fig. 4.

The scaffold illustrated in Figs. 1 and 2 is formed of two units as this makes a very convenient size of scaffold for many uses, but it should be understood that only a single unit may be used, or the scaffold may comprise three or 15 more units where a longer platform is desirable or necessary.

Each unit of the scaffold comprises two upright supporting frames each of which may comprise a pair of spaced uprights 10 rigidly connected at 20 their lower ends to two fixed horizontally disposed base members 11 which may be provided with casters 12 so that the scaffold may be easily moved across a floor, and connected at their ends to a rigid cross bar 13. The uprights 10 of each 15 supporting frame may be braced by the crossed struts 14 offset from the supporting frames as by the blocks 15 having a purpose to be herein-after described.

The pair of upright supporting frames for each 30 unit may be adjustably connected together as by lazy tong levers 16, each of these levers being pivotally connected at its upper end to one of the uprights 10, as indicated at 17, while the lower end thereof is pivotally connected as at 18 to a 35 cross bar 19 vertically, slidably movable upon the uprights 10 of the other upright supporting frame of the unit.

The slidably movable cross bars 19 are slidably 40 movable upon the lower portions of the uprights 10 and a clearance is provided to permit them to slide from the upper position as shown in Fig. 1 to the lower position shown in Fig. 2, by offsetting the struts 14 upon the blocks 15.

For the purpose of mounting a platform at 45 any desired height upon the upright supporting frames the vertically adjustable cross bars 20 are slidably mounted upon the uprights 10 of each upright supporting frame, above the fixed cross bars 13.

Each of these adjustable cross bars comprises a metal loop 21 slidably located around both of the uprights 10 of each upright supporting frame and having a wood block 22 mounted therein between the uprights 10. This wood block is longitudinally adjustably mounted within the metal loop

21 by means of pins 23 carried by the block and located through slots 24 in the loop.

For the purpose of clamping each of the adjustable cross bars 20 in any desired adjusted position upon the supporting frames, a clamping plate 25 is slidably mounted upon each metal loop 21 between one end of the loop and the adjacent upright 10, and a clamping screw 26 is threaded through this end of the loop and bears against the clamping plate 25 so that when the screw 26 is tightened, the metal loop 21 will be drawn tightly around the two uprights 10 of the supporting frame, clamping them against opposite ends of the wood block 22, which has sufficient longitudinal movement relative to the metal loop to accomplish this purpose, by means of the pins 23 and slots 24.

Spring loaded rods 20a may depend from the lower sides of the adjustable cross bars 20, being located through suitable apertures in the fixed cross bars 13 and the slideable cross bars 19, for the purpose of normally urging the adjustable cross bars 20 upward upon the upright supporting frames.

A section 27 of the platform is provided for each unit of the scaffold and as shown in the drawing, one end of each platform section may be hingedly connected to the adjustable cross bar 20 of one upright supporting frame as indicated at 28 in Fig. 3, while the free end of the platform section is adapted to rest upon the adjustable cross bar 20 of the other upright supporting frame of the unit, as shown in Figs. 1 and 3 of the drawing.

In the form of the invention illustrated where the scaffold comprises two units, the two platform sections are preferably hingedly connected to the adjustable cross bar 20 of the central frame and the free ends of the platform sections are adapted to rest upon the adjustable cross bars 20 of the two endmost supporting frames.

Each of the platform sections 27 may be provided with sockets 29 on its underside near its free end to engage the studs 30 fixed to the upper side of the wood block 22 of the adjacent adjustable cross bar 20 so as to temporarily lock these parts together with the platform in open position as best shown in Fig. 3.

A ladder, indicated generally at 31, may be pivotally connected to the upper ends of the uprights 10 of one endmost upright supporting frame, as indicated at 32, and provided with the usual links 33 for holding the ladder in operative or folded condition as may be desired.

As best shown in Fig. 1 the top step of the ladder may be formed by the free end of the platform section 27 resting upon the adjacent cross bar 20.

From the above it will be seen that the platform may be easily and quickly adjusted to any desired height by loosening the clamping screws 26 and raising or lowering the adjustable cross bars 20 to the desired height, the clamping screw 26 being then tightened to hold the cross bars 20 at the adjusted height, the platform sections 27 being supported upon the cross bars 20 at the adjusted height.

To fold or collapse the scaffold, to the position shown in Fig. 2, the clamping screws 26 of the adjustable cross bars 20 on the two endmost supporting frames are loosened and the adjustable bars moved downward until the free ends of the platform sections 27 will clear the cross bars 20 and swing downward to substantially vertical position as shown in Fig. 2.

The several vertical supporting frames are then moved toward each other collapsing the lazy tong levers 16 to the position shown in Fig. 3 and in this position, the scaffold may be easily transported or may be stored within a minimum space.

I claim:

1. A collapsible platform scaffold comprising a pair of upright supporting frames, lazy tong levers pivotally connected at their upper ends to said frames, cross bars slidably mounted upon the frames, the lower ends of the lazy tong levers being pivotally connected to said cross bars, vertically adjustable members on the upper portions of the frames, means for clamping said adjustable members in adjustable position, a platform hingedly connected at one end to one of said vertically adjustable members, the free end of the platform being arranged to be supported upon the other vertically adjustable member.
- 10 2. A collapsible platform scaffold comprising a pair of upright supporting frames, lazy tong levers pivotally connected at their upper ends to said frames, cross bars slidably mounted upon the frames, the lower ends of the lazy tong levers being pivotally connected to said cross bars, vertically adjustable members on the upper portions of the frames, means for clamping said adjustable members in adjustable position, a platform hingedly connected at one end to one of said vertically adjustable members, the free end of the platform being arranged to be supported upon the other vertically adjustable member, and means for attaching the free end of the platform to said other vertically adjustable member.
- 15 3. A collapsible platform scaffold comprising a pair of upright supporting frames, lazy tong levers pivotally connected at their upper ends to said frames, cross bars slidably mounted upon the frames, the lower ends of the lazy tong levers being pivotally connected to said cross bars, vertically adjustable members on the upper portions of the frames, means for clamping said adjustable members in adjustable position, a platform hingedly connected at one end to one of said vertically adjustable members, the free end of the platform being arranged to be supported upon the other vertically adjustable member, and a pin upon said other vertically adjustable member, there being a socket in the under side of the free
- 20 45 50 end of the platform for receiving said pin.
4. A collapsible platform scaffold comprising a pair of upright supporting frames, lazy tong levers pivotally connected at their upper ends to said frames, cross bars slidably mounted upon the frames, the lower ends of the lazy tong levers being pivotally connected to said cross bars, vertically adjustable cross bars on the upper portions of the frames, each vertically adjustable cross bar including a loop portion slidably mounted on the frame, a clamping screw located through one end of said loop portion for engagement with the adjacent edge of the frame, a platform hingedly connected at one end to one of said adjustable cross bars, the free end of the platform being arranged to be supported upon the other adjustable cross bar.
5. A collapsible platform scaffold comprising a pair of upright supporting frames, each of which includes two spaced uprights and fixed cross members at their lower ends and intermediate their ends, lazy tong levers pivotally connected at their upper ends to the upper ends of the uprights, cross bars slidably mounted upon the uprights between said intermediate and lower fixed cross members, the lower ends of the lazy tong
- 25 30 35 40 45 50 55 60 65 70 75 80 85 90 95

levers being pivotally connected to said sliding cross bars, vertically adjustable cross bars mounted upon the uprights above said intermediate fixed cross bars, each adjustable cross bar comprising a metal loop located around the uprights, a block longitudinally movably mounted in the loop between the uprights and a clamping screw in one end of the loop for clamping the adjustable cross bar in adjusted position upon the uprights, and a platform supported upon the adjustable cross bar.

6. A collapsible platform scaffold comprising a pair of upright supporting frames, each of which includes two spaced uprights and fixed cross members at their lower ends and intermediate 5 their ends, lazy tong levers pivotally connected at their upper ends to the upper ends of the uprights, cross bars slidably mounted upon the up-

rights between said intermediate and lower fixed cross members, the lower ends of the lazy tong levers being pivotally connected to said sliding cross bars, vertically adjustable cross bars mounted upon the uprights above said intermediate fixed cross bars, each adjustable cross bar comprising a metal loop located around the uprights, a block longitudinally movably mounted in the loop between the uprights, and a clamping screw in one end of the loop for clamping the adjustable cross bar in adjusted position upon the uprights, and a platform hingedly connected at one end to one vertically adjustable cross bar, the free end of the platform being arranged to be supported upon the other vertically adjustable cross bar.

HOMER B. WALTZ.
